I claim the ornamental design for a toilet, as shown and described.

DESCRIPTION

FIG. 1 is a perspective view of a toilet, showing my new design;

FIG. 2 is another perspective view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1; and,

FIG. 8 is a bottom plan view of FIG. 1.

The broken lines represent portions of the toilet that form no part of the claimed design. The dash dot broken lines shown in the figures depict boundaries of the claim and form no part thereof.
